[57] CLAIM

The ornamental design for a cooling fan assembly housing for electrical equipment shown and described.

DESCRIPTION

FIG. 1 is a top perspective view of a cooling fan assembly housing for electrical equipment showing my new design;

FIG. 2 is a right side elevational view thereof;

FIG. 3 is a left side elevational view thereof;

FIG. 4 is a top plan view thereof, the bottom being a mirror image;

FIG. 5 is a front elevational view thereof; and

FIG. 6 is a rear elevational view thereof.

FIG 1

FIG 2

FIG 3

FIG 4

FIG 5

FIG 6
